Primary Examiner — Justin C Dodson

Assistant Examiner — Matthew Bird

(74) Attorney, Agent, or Firm — MUNCY, GEISSLER,
OLDS & LOWE, P.C.(57) **CLAIM**

The ornamental design for a fan as shown and described.

DESCRIPTION

FIG. 1 is a perspective view of a fan, showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a reference view representing that the fan is
assembled to a frame; and,FIG. 10 is another reference view representing that the fan
is assembled to the frame.The broken lines throughout the views form no part of the
claimed design.**1 Claim, 10 Drawing Sheets**(56)
